Inventor
W. P. Goolman

UNITED STATES PATENT OFFICE.

W. P. GOOLMAN, OF INDIANAPOLIS, INDIANA, ASSIGNOR TO GOOLMAN, MORRIS & CO., OF SAME PLACE.

STRAW-CUTTER.

Specification forming part of Letters Patent No. 14,042, dated August 30, 1864.

To all whom it may concern:

Be it known that I, W. P. GOOLMAN, of Indianapolis, Marion county, and State of Indiana, have invented a new and useful Machine for Cutting Straw, called "Goolman's Cutting-Box;" and I do hereby declare that the following is a full, clear, and exact description of the construction and operation of the same, reference being had to the annexed drawings, making a part of this specification, in which—

Figure 1 is a perspective view; Figs. 2, 3, and 4, details; and 5, 6, and 7 sections.

The nature of my invention consists in using a triangular box, N, through which passes the stud P. Attached to this stud is the lever F with knife G, the gage-plate E, which is fastened to the lever at K by means of the set-screw C.

P represents the stud, and P' the flanges of the same. 5, 6, and 7 represent the box N, and T the washer which presses upon the india-rubber packing X, between the box-ring S and the stud P.

W represents the ring of gage plate E, by means of which the plate is fastened to the lever at K.

R represent the ends of stud, which are provided with a screw.

M and U are the nuts. L is the washer, and F is the lever, to which is attached the knife G.

D is the mouth-piece, with its projections Y, against which the knife G works in cutting the straw.

A A represent the box; C, the cover, and B B B the frame-work.

Q is the stop or check for the knife.

H is the handle of lever F.

X represents the india-rubber.

Operation: The tightening of the nut at the rear end of screw on stud P against the washer T and the rubber X causes the stud P to press against the three set-screws a a a, and permits any desired adjustment of the knife G to the mouth-piece D by changing any one or all the three screws.

I do not claim adjusting the knife by means of the set-screws a a a, for I am aware that this has been done before; but

What I claim, and desire to secure by Letters Patent of the United States, is—

The combination of the box N with the stud P and set-screws a a a, the elastic substance X, the washer T and nut U, all arranged and operating substantially as and for the purpose shown and described.

W. P. GOOLMAN.
